N. Y.

Application May 27, 1948, Serial No. 29,508

20 Claims. (Cl. 164—52)

1

This invention relates to hydraulic hold-down means for power shears and analogous machines.

Conventional hold-down means for holding metal or other sheets to a work table during shearing or the like involve mechanically driven reciprocating means, usually spring-cushioned. Such hold-down devices are simple, inexpensive and free of trouble, as compared with conventional hydraulic hold-down devices presently known and available. Also the energy put in to compress the springs in mechanical hold-downs is returned to the system on the up stroke.

Nevertheless, advantages are to be derived from the use of hydraulically operated hold-down means, despite the fact that all the prior means offered to provide such a device have been subject to various objections, among them the cyclical action heretofore considered inherent in the problem, matters of objectionable leakage, and the amount of energy required to displace considerable quantities of liquid and develop the necessary pressure therein.

According to the present invention hydraulic hold-down means are provided which provide a satisfactory and practical solution of the various problems which have heretofore militated against the successful and practical employment of hydraulic pressure for hold-down purposes in place of the usual mechanically driven spring cushioned hold-downs.

According to the present invention the hydraulic pressure generating means is continuous in operation, not cyclical or intermittent as in prior proposals, and the arrangement is such that full hold-down pressure is applied almost instantaneously when desired, rather than with a material time lag. Further, the arrangement of the present invention is such that the work of operating the hold-down and providing hold-down pressure is removed from the machine drive proper which reduces the strength requirements of the machine and simplifies the construction thereof.

The almost complete elimination of moving parts in the hold-down provides a very quiet operation and a small pump is adequate to provide full hold-down pressure requirements. If desired the pump may be driven from one of the gears in the conventional shear drive gear box instead of by a separate electric motor, but in either event the advantage of low power requirement is present. Further, the provision of hydraulic pressure means which are independent of the shear proper permits the hold-down to be operated at will without setting the shearing or other mechanism

2

in motion, and this is of particular advantage when cutting a sheet without using a fixed, positive back gauge, as in cutting along a line or to a measured dimension.

5 Since the main supporting bar for the hydraulically operated hold-down feet is stationary, it serves as a rigid structural tie between the end housings of the shear and thus strengthens the machine and minimizes the need of other cross-bracing components between the end housings. Of course, the provision of a stationary hold-down bar also eliminates all of the usual guides and slide-bearing surfaces normally associated with mechanically reciprocating shear hold-downs and makes for a safer and less hazardous machine.

10 In the hold-down means of the present invention the hold-down feet are in contact with the work, resting thereon with the force of gravity only, prior to the application of hydraulic hold-down pressure. This prevents marring the surface of the sheet which often results when various impact hold-down means are employed. This is of particular importance when operating upon polished sheets of aluminum or stainless steel. This arrangement also eliminates the possibility of a workman accidentally getting his fingers under the hold-down feet.

15 Various embodiments of the principles of the present invention are illustrated in the accompanying drawings and described in detail in the ensuing specification by way of example. However, many modifications may be made within the spirit and scope of the invention and without departing from the principles thereof, the invention being limited only as defined in the appended claims.

20 In the drawings:

Fig. 1 is a front elevational view of a power shear showing one form of hold-down bar and hydraulic cylinder means for holding a sheet to the work table of the shear;

Fig. 2 is a general schematic view of the hydraulic circuit in one form of the present invention;

Fig. 3 is another general schematic view of another adaptation of the hydraulic circuit of the present invention having a modified form of control means;

Fig. 4 is a fragmentary elevational view of a hold-down bar provided with one form of hydraulic hold-down means;

Fig. 5 is a cross-sectional view taken on the line 55 V—V of Fig. 4;

Fig. 6 is a cross-sectional view taken on the line VI—VI of Fig. 4;

Fig. 7 is a view similar to Fig. 4 but showing another form of hydraulic hold-down means;

Fig. 8 is a cross-sectional view taken on the line VIII—VIII of Fig. 7;

Fig. 9 is a cross-sectional view taken on the line IX—IX of Fig. 7;

Fig. 10 is another view similar to Fig. 4 but showing still another form of hydraulic hold-down means;

Fig. 11 is a cross-sectional view taken on the line XI—XI of Fig. 10; and

Fig. 12 is a cross-sectional view taken on the line XII—XII of Fig. 10.

Throughout the several figures of the drawings like characters of reference denote like parts and, referring to Fig. 1, the power squaring shear there shown comprises a pair of end housing members 15 and 16 which support therebetween a bed 17 having a work receiving table 18.

The shear includes a main drive shaft 19 having eccentric or crank connection with the crosshead 20 in conventional manner, the latter carrying a shear blade 21. In Fig. 1 the numeral 24 designates a hold-down bar which is rigidly fixed at its opposite ends to end housings 15 and 16 as at 25 and 26. Hold-down bar 24 includes a series of hydraulic cylinders 27, each of which has a work clamp foot 28 at its lower end.

The details of construction and operation of the hydraulic cylinders and their associated hold-down feet will be described in detail later herein in several forms. Fig. 1 shows schematically the hold-down bar 24 and hydraulic cylinders 27. In Fig. 2, a liquid reservoir or supply is indicated schematically at 30 and a continuous operating pump, which may be of relatively low displacement, has its intake port in free communication with the interior of the reservoir as by means of conduit 32. Pump 31 has an outlet conduit 33 which leads to a branch conduit 34 leading back to the reservoir and also a branch conduit 35 leading to hold-down bar 24.

At hold-down bar 24 branch conduit 35 communicates with a fluid passage 36 which is associated with the hold-down bar and communicates freely with all of the hydraulic cylinders 27 by means of branch passages 39. Another branch conduit 40 from conduit 35 leads back to the interior of reservoir 30 and includes a manually operable valve 42 and a second control valve 43. Control valve 43, which is normally open, may be conveniently attached to the frame of the shear as shown in Fig. 1 and includes a valve closing element 44 adapted to be actuated by a cam 45 located upon drive shaft 19. Manual valve 42 is selectively closable to operate the hold-down independently of the shear crosshead for placing work to be cut to a line or to a measured dimension.

In Fig. 2 the numeral 50 designates a pressure limiting valve which determines the maximum pressure that pump 31 delivers to conduit 35. Valve 50 normally prevents flow into conduit 34 from conduit 33 but any excessive pressure in conduit 33 causes pressure limiting valve 50 to open and relieve the excess pressure by exhausting through conduit 34 back to the reservoir. Passage 36 of hold-down bar 24 is provided, at the end opposite the connection with conduit 35, with a capillary tube 52 or any tube having a very small inside diameter leading therefrom back to reservoir 30. When the shear is in condition for operation, but is not executing a shearing stroke, valve 42 is open and valve 43 is closed, liquid is supplied to the hydraulic cylinders 27 through conduit 35 and passage 36, and the shear is held down by the weight of the workpiece.

valves 42 and 43 are open, and the liquid displaced by pump 31 and flowing through conduit 35 bypasses back to the reservoir through passage 49, at the same time maintaining the passage 36 and hydraulic cylinders 27 full of liquid.

Attention will now be given to Figs. 4, 5, and 6, which show one embodiment of hold-down bar 24, hydraulic cylinders 27 and hold-down feet 28. In Fig. 4 the hold-down bar 24 comprises upper and lower bar portions 60 and 61 which are welded into an integral unit as at 63 and 64. Before welding, the upper surface of bar 61 is milled or otherwise machined to provide a groove 65 extending from near one end of bar 61 to the other, stopping just short of the end of the bar in each instance. When bars 60 and 61 are joined by welding as just described, groove 65 cooperates with the under side of bar 60 to form the liquid passage 36 of Fig. 2. Communicating with this passage is an entrance passage 67 which is connected to conduits 35 and 40.

In the schematic view, Fig. 2, conduit 36 is shown as declining to the left as there viewed. In Fig. 4 the same substantive effect is attained by disposing passage 67 at a higher elevation than passage 36. By reason of this arrangement passage 36 will be maintained full of liquid by pump 31 even though bypass 40 is freely open to bypass excessive liquid back to reservoir 30. This also maintains the several hydraulic cylinders 27 in a filled condition.

In the form shown in Figs. 4, 5, and 6, each hydraulic cylinder 27 has a threaded upper end 70 screwed into the under side of bar 61 and suitably packed as indicated at 71. Hydraulic cylinder 27 has a fluid chamber 72 and a passage 73 leading upwardly therefrom in registry with a passage 75 which is formed in bar 61 and extends downwardly from groove 65, there being a separate passage 75 in the hold-down bar 24 for each hold-down cylinder 27. Thus, passage 36 is in free communication with the fluid chamber 72 in each of the hydraulic cylinders 27. Each of the hold-down feet 28 has an upper piston portion 77 fixed thereto and disposed for vertical sliding movement in fluid chamber 72 of cylinder 27.

In the form shown in Figs. 4 through 6, the hold-down foot proper is generally rectangular, as viewed in plan and the bottom of cylinder 27 is bifurcated as at 80 to receive hold-down foot 28 and hold the same against rotation. The forward lower edge of each hold-down foot 28 is rounded or beveled as indicated at 81 to facilitate moving a metal sheet or the like thereunder as at 83 in Figs. 4 and 5. The hold-down feet 28 are normally in a lowered position against the work table 18 but under no pressure, resting there by gravity alone, so that a sheet may simply be pushed beneath the several hold-down feet, whereupon they move upwardly a distance equal to the thickness of the sheet and rest lightly on the upper surface of the sheet, the oil from the cylinder being displaced by way of passage 40.

As shown in Fig. 5, the inner wall of cylinder 27 has an encircling oil collecting groove 86 and passages 87 and 88 lead therefrom to a leakage collecting conduit 89 which may communicate in common with all of the several hydraulic cylinders and have gravity flow back to reservoir 30 as at 90 in Fig. 2.

As the crosshead 20 begins to descend in commencing a shearing stroke, cam 45 engages operator 44 to close the normally open hold-down valve 42. Since pump 31 is in

continuous operation and the passage 36 and the passages leading therefrom are all in a liquid-filled condition, pressure against hold-down feet 28 through the medium of pistons 77 is substantially immediate and direct. There is no necessity for any movement of the piston 77 in cylinders 27 and an immediate and secure hold-down action results.

Each piston 77 fits rather closely in cylinder 27 both above and below the oil collecting groove 86. Accordingly, such liquid as passes downwardly about the piston to the oil collecting groove, because of the considerable pressure in chamber 72 during a hold-down operation, flows into the substantially pressureless collecting groove and thence outwardly through passages 87 and 88 to leakage conduit 89 and back to the reservoir. Since it requires a considerable pressure to move liquid past piston 77 at any point along cylinder 27, there will be substantially no tendency for liquid to pass below the collecting groove 86.

Because there is only the minute axial movement of piston 77 in cylinder 27 equal to the thickness of the metal being sheared, there is relatively no tendency for a film of oil to be continuously moved downwardly between piston 77 and the interior wall of cylinder 27, as might be the case if sliding movement of greater magnitude were necessary in operating the hold-down.

The relatively minute but substantially continuous flow of liquid from the left-hand end of passage 36 through capillary tube 52 whenever passage 36 is under pressure carries off any air which may be entrained with the liquid in passage 36.

Reference will now be had to the modified hydraulic hold-down system shown schematically in Fig. 3. In this form of the invention, as in the case of the embodiment of Fig. 2, there is a stationary hold-down bar 95 having a plurality of hydraulic hold-down cylinders 96 and a common pressure supply passage 97. In Fig. 3 the pressure generating pump is designated 100 and its outlet passage 101 is connected with a conduit 102 leading to the cylinder supply passage 97.

Interposed between the outlet passage 101 and conduit 102 is a pressure limiting valve 103 with a conduit 104 for returning liquid to a reservoir 105 when the pressure output of pump 100 exceeds the pressure setting of valve 103. The intake conduit of pump 100 is designated 107 and leads from reservoir 105.

As in the previous instance, the pressure supply passage 97 of the hydraulic cylinders terminates in communication with a capillary tube 110 which leads back to reservoir 105 in the same manner and for the same purpose set forth in connection with the description of Fig. 2. In Fig. 3 the leakage return conduit similar to that designated 89 in Fig. 2 is designated 111.

In addition to pressure passage 97 for the hydraulic cylinders, conduit 102 communicates with a bypass conduit 112 which leads back to reservoir 105 and has interposed therein a solenoid controlled valve 113 which is normally open and is closable upon energization of an electromagnet 114. In this form of the invention the single valve 113 is operated either manually or automatically. Manual operation is provided for operating the hold-down independently of the shear crosshead and automatic operation accompanies reciprocating movement of the shear crosshead.

A supply circuit for energizing electromagnet 114 is designated 115 and has connected in paral-

lel thereto a manual normally open treadle operated switch 116 and a second normally open switch 117 which replaces the valve 43 in Fig. 1 so that cam 44 of the drive shaft of the machine acts upon an operator 118 of the switch to automatically close the same for predetermined periods during the reciprocation of the shear crosshead. It is believed that the operation of the electrically controlled hydraulic hold-down system of the embodiment of Fig. 3 will be clear from the foregoing.

A second embodiment of the hold-down bar and hydraulic cylinder means per se is illustrated in Figs. 7, 8, and 9. In this form the pressure and leakage conduits for the cylinders are independent of the hold-down bar proper and the entire cylinder and conduit assembly is removable from the stationary hold-down bar.

Referring to Figs. 7 and 8 the numeral 120 designates a hold-down bar similar to the bar 24 of Figs. 1, 2, 4 and 5 and one of a series of hydraulic cylinder elements is designated 121. As in the preceding instance, cylinder 121 has a pressure chamber 122, a piston 123 vertically slidably therein, and an oil collecting groove 124 about its inner periphery. Piston 123 is provided at its lower end with a hold-down foot 126 similar to that previously described and the lower portion of cylinder 121 is bifurcated as at 128 to guide hold-down foot 126 against rotative movement.

Cylinder 121 is secured against the under side of hold-down bar 120 by means of screws 130 which extend upwardly through lugs 131 which project from opposite sides of cylinder 121.

Cylinder 121 has a forwardly offset upper extension 134 and the several upward extensions 134 of a series of hydraulic cylinders are connected by pressure conduits 135 and leakage return conduits 136. Pressure conduits 135 apply operating pressure to pressure chamber 122 by means of passages 137, 138, and 139 formed in each of the upward extensions 134 of the hydraulic cylinders 121. As appears best in Fig. 7, the liquid collecting groove 124 communicates with leakage return conduits 136 by means of passages 141, 142, and 143 formed in the body portion of cylinder 121 and upward extension 134.

In the further embodiment of the hydraulic cylinder means per se illustrated in Figs. 10 through 12, the numeral 150 designates one of a series of hydraulic cylinders having lateral lugs 151 at its upper end for securement to the under side of a hold-down bar 152 by means of screws 153.

Hydraulic cylinder 150 has a pressure chamber for receiving a piston 156 and the latter has a hold-down foot 157 at its lower end as in the previously described embodiments. Cylinder 150 is bifurcated at its lower end as at 158 to prevent rotation of the hold-down foot. The inner periphery of the pressure chamber 155 of cylinder 156 is provided with a leakage collecting groove 160 as in the previously described embodiments.

The upper end of cylinder 150 has a forwardly offset portion 161 for connection with pressure conduit means 163 and leakage conduit means 164. Pressure conduit means 163 connects with pressure chamber 155 of hydraulic cylinder 150 by means of a passage 166 formed in extension 161 of cylinder 150, and leakage collecting groove 160 of cylinder 150 connects with leakage conduit 164 by means of passages 170 and 171 formed in cylinder 150.

A guard plate 175 depends from a bar 176 to which it is fixed by welding or the like and bar 176 is secured to hold-down bar 152 by means of screws 177. Guard plate 175 extends downwardly behind cylinders 150 to a point just above work table 18 to prevent an operator from reaching under the hold-down bar between a pair of spaced cylinders 150. Similar guard plates are intended to be employed in conjunction with the previously described hydraulic cylinder embodiments, the guard plate of the first described embodiment being designated 180 in Fig. 4.

The operation of the several forms of hydraulic cylinder arrangements illustrated herein is the same in function and theory as described generally in connection with the schematic hydraulic circuit, Fig. 2, and obviously any of the cylinder arrangements of Figs. 4 through 12 may be used in the systems of either Figs. 2 or 3.

What is claimed is:

1. A hold-down for shears and like machines, said hold-down comprising a rigid support, hydraulic pressure actuated hold-down means supported thereby, a pressure conduit for energizing said pressure actuated hold-down means by application of hydraulic pressure thereto, a continuously operating pressure generator in free continuous communication with said pressure conduit, a normally open relief conduit between said pressure generator and said pressure conduit to relieve the pressure conduit, valve means in said relief conduit closable to prevent flow therein and thus cause the pressure generator to act directly against the pressure conduit to activate the hold-down means, and means operable in timed relation with the operation of the machine proper for automatically closing and opening said valve at predetermined points in the cycle of operation of the machine.

2. A hold-down for shears and like machines, said hold-down comprising a rigid support, hydraulic pressure actuated hold-down means supported thereby, a pressure conduit for energizing said pressure actuated hold-down means by application of hydraulic pressure thereto, a continuously operating pressure generator in free continuous communication with said pressure conduit, a normally open relief conduit between said pressure generator and said pressure conduit to relieve the pressure conduit, and valve means in said relief conduit closable to prevent flow therein and thus cause the pressure generator to act directly against the pressure conduit to activate the hold-down means, means operable in timed relation with the machine proper for automatically closing and opening said valve at predetermined points in the cycle of operation of the machine, and manual means for selectively closing said relief conduit to activate the hold-down means independently of machine operation.

3. A hold-down for shears and like machines, said hold-down comprising a rigid support, a hydraulic pressure actuated hold-down means supported thereby, a pressure conduit for energizing said pressure actuated hold-down means by application of hydraulic pressure thereto, a continuously operating pressure generator in free continuous communication with said pressure conduit, a normally open relief conduit in open communication with said pressure conduit to relieve the pressure conduit, and means for closing said relief conduit automatically for operating said hold-down in timed relation with the operation of the machine proper and manu-

ally for operating the hold-down independently of machine operation.

4. A hold-down for shears and like machines, said hold-down comprising a rigid support, hydraulic pressure actuated hold-down means supported thereby, a pressure conduit for energizing said pressure actuated hold-down means by application of hydraulic pressure thereto, a continuously operating pressure generator in free continuous communication with said pressure conduit, a normally open relief conduit in open communication with said pressure conduit to relieve the pressure conduit, means for closing said relief conduit automatically in timed relation with the operation of the machine proper to activate the hold-down means, and means for closing the relief conduit by manual operation to activate the hold-down means independently.

5. A hold-down for shears and like machines, said hold-down comprising a rigid support, hydraulic pressure actuated hold-down means supported thereby, a pressure conduit for energizing said pressure actuated hold-down means by application of hydraulic pressure thereto, a continuously operating pressure generator in free continuous communication with said pressure conduit, a normally open relief conduit between said pressure generator and said pressure conduit to relieve the pressure conduit, and valve means in said relief conduit automatically closable in timed relation with the operation of the machine proper to cause the pressure generator to act directly against the pressure conduit to activate the hold-down means.

6. A hold-down for shears and like machines, said hold-down comprising a rigid support, hydraulic pressure actuated hold-down means supported thereby, a pressure conduit for energizing said pressure actuated hold-down means by application of hydraulic pressure thereto, a continuously operating pressure generator in free continuous communication with said pressure conduit, a normally open relief conduit between said pressure generator and said pressure conduit to relieve the pressure conduit, and valve means in said relief conduit automatically closable in timed relation with the operation of the machine proper to cause the pressure generator to act directly against the pressure conduit to activate the hold-down means, said valve means being manually closable to activate the hold-down means independently of the operation of the machine proper.

7. A hold-down for shears and like machines, said hold-down comprising a rigid support, hydraulic pressure actuated hold-down means supported thereby, a pressure conduit for energizing said pressure actuated hold-down means by application of hydraulic pressure thereto, a continuously operating pressure generator in free continuous communication with said pressure conduit, a normally open relief conduit between said pressure generator and said pressure conduit to relieve the pressure conduit, valve means in said relief conduit automatically closable in timed relation with the operation of the machine proper to cause the pressure generator to act directly against the pressure conduit to activate the hold-down means, and other valve means in said relief conduit selectively closable to activate the hold-down means independently of the operation of the machine proper.

8. A hold-down for shears and like machines, said hold-down comprising a rigid support, hydraulic pressure actuated hold-down means

supported thereby, a pressure conduit for energizing said pressure actuated hold-down means by application of hydraulic pressure thereto, a continuously operating pressure generator in free continuous communication with said pressure conduit, a normally open relief conduit between said pressure generator and said pressure conduit to relieve the pressure conduit, and a normally open valve in said relief conduit, means for automatically closing said valve in timed relation with the operation of the machine proper to cause the pressure generator to act directly against the pressure conduit to activate the hold-down means, and other means manually operable for closing said valve to activate the hold-down means independently of machine operation.

9. Hold-down means for shears and like machines, said hold-down means comprising a rigid support, a plurality of hydraulic hold-down cylinders supported thereby, piston means in said cylinders adapted to be urged downwardly against a work piece upon application of hydraulic pressure to said cylinders, a common pressure conduit for said cylinders, a continuously operating pressure generator in free continuous communication with said common pressure conduit, a relief conduit between said pressure generator and said common pressure conduit to relieve the pressure conduit, and valve means in said relief conduit closable to prevent bypass of said pressure conduit and thus cause the pressure generator to act directly against the common pressure conduit.

10. A hold-down for shears and like machines, said hold-down comprising a rigid support, a plurality of hydraulic pressure actuated hold-down means supported thereby, a common pressure conduit for energizing said pressure actuated hold-down means, a continuously operating pressure generator in free continuous communication with said common pressure conduit, a relief conduit between said pressure generator and said common pressure conduit to relieve the pressure conduit, and valve means in said relief conduit closable to prevent bypass of said pressure conduit and thus cause the pressure generator to act directly against the common pressure conduit.

11. Hold-down means for shears and like machines, said hold-down means comprising a rigid support, a plurality of pairs of piston and cylinder elements including fluid pressure chambers, one of each of said pairs of elements being fixed to the support and the other normally resting on the work table under the force of gravity whereby a work piece may be slipped thereunder, a common pressure conduit in communication with the several fluid pressure chambers, a continuously operating pressure generator in free continuous communication with said common pressure conduit, a relief conduit between said pressure generator and said common pressure conduit to relieve the pressure conduit, and valve means in said relief conduit closable to prevent bypass of said common pressure conduit and thus cause the pressure generator to act directly against the common pressure conduit and the several fluid pressure chambers and thus cause said other of the pairs of piston and cylinder elements to be urged downwardly against the work piece.

12. Hold-down means for shears and like machines, said hold-down means comprising a rigid support, a plurality of pairs of piston and cylinder elements, said cylinder elements being fixed

to the support and having fluid pressure chambers, the piston elements normally resting on the work table under the force of gravity whereby a work piece may be slipped thereunder, a common pressure conduit in communication with the several fluid pressure chambers, a continuously operating pressure generator in free continuous communication with said common pressure conduit, a relief conduit between said pressure generator and said common pressure conduit to relieve the pressure conduit, and valve means in said relief conduit closable to prevent bypass of said common pressure conduit and thus cause the pressure generator to act directly against the common pressure conduit and the several fluid pressure chambers and thus cause said other of the pairs of piston and cylinder elements to be urged downwardly against the work piece.

20 13. Hold-down means for shears and like machines, said hold-down means comprising a rigid support, a pair of piston and cylinder elements including a fluid pressure chamber, one of said pair of elements being fixed to the support and the other normally resting on the work table under the force of gravity whereby a work piece may be slipped thereunder, a continuously operating pressure generator in free continuous communication with said pressure chamber, a relief conduit between said pressure generator and said pressure chamber to relieve the pressure chamber, and valve means in said relief conduit closable to prevent bypass of said pressure chamber and thus cause the pressure generator to act directly against said other of the pair of piston and cylinder elements to urge the same downwardly against the work piece.

40 14. Hold-down means for shears and like machines, said hold-down means comprising a rigid support, a pair of piston and cylinder elements, said cylinder elements being fixed to the support and having a fluid pressure chamber and the piston element normally resting on the work table under the force of gravity whereby a work piece may be slipped thereunder, a continuously operating pressure generator in free continuous communication with said fluid pressure chamber, a relief conduit between said pressure generator and said pressure chamber to relieve the pressure chamber, and valve means in said relief conduit closable to prevent bypass of said pressure chamber and thus cause the pressure generator to act directly against the piston element and thus cause said piston element to be urged downwardly against the work piece.

55 15. A hold-down for shears and like machines, said hold-down comprising a rigid support, hydraulic pressure actuated hold-down means supported thereby, a pressure conduit for energizing said pressure actuated hold-down means by application of hydraulic pressure thereto, a continuously operating pressure generator in free continuous communication with said pressure conduit, a normally open relief conduit between said pressure generator and said pressure conduit leading therefrom at an elevated point relative to the pressure conduit to relieve the pressure conduit of fluid pressure without permitting liquid drainage therefrom, and valve means in said relief conduit closable to cause the pressure generator to act directly against the pressure conduit to activate the hold-down means.

70 16. A hold-down for shears and like machines, said hold-down comprising a rigid support, hydraulic pressure actuated hold-down means sup-

11

ported thereby, a pressure conduit for energizing said pressure actuated hold-down means by application of hydraulic pressure thereto, a continuously operating pressure generator in free continuous communication with said pressure conduit, a normally open relief conduit between said pressure generator and said pressure conduit to relieve the pressure conduit, valve means in said relief conduit automatically closable in timed relation with the operation of the machine proper to cause the pressure generator to act directly against the pressure conduit to activate the hold-down means, and a capillary tube leading from said pressure conduit beyond said hydraulic pressure actuated hold-down means to carry off air which may be entrained with the hydraulic medium in said pressure conduit.

17. A hold-down for shears and like machines, said hold-down comprising a rigid support, hydraulic pressure actuated hold-down means supported thereby, a pressure conduit for energizing said pressure actuated hold-down means by application of hydraulic pressure thereto, a continuously operating pressure generator in free continuous communication with said pressure conduit, a normally open relief conduit between said pressure generator and said pressure conduit leading therefrom at an elevated point relative to the pressure conduit to relieve the pressure conduit of fluid pressure without permitting liquid drainage therefrom, valve means in said relief conduit closable to cause the pressure generator to act directly against the pressure conduit to activate the hold-down means, and a capillary tube leading from said pressure conduit beyond said hydraulic pressure actuated hold-down means to carry off air which may be entrained with the hydraulic medium in said pressure conduit.

18. Hold-down means for shears and like machines, said hold-down means comprising a rigid support, a pair of inter-sliding piston and cylinder elements including a fluid pressure chamber, one of said pair of elements being fixed to the support and the other normally resting on the work table under the force of gravity whereby a work piece may be slipped thereunder, the fixed element having an encircling groove at its point of inter-sliding engagement with said other element, and a conduit for draining leakage liquid from said groove, a continuously operating pressure generator in free continuous communication

12

with said fluid pressure chamber, a relief conduit between said pressure generator and said pressure chamber to relieve the pressure chamber, and valve means in said relief conduit closable to prevent bypass of said fluid pressure chamber and thus cause the pressure generator to act directly against said other of the pair of piston and cylinder elements to urge the same downwardly against the work piece.

19. Hold-down means for shears and like machines, said hold-down means comprising a rigid support, a plurality of hydraulic hold-down cylinders supported thereby, piston means in said cylinders adapted to be urged downwardly against a work piece upon application of hydraulic pressure to said cylinders, a common pressure conduit for said cylinders, a continuously operating pressure generator in free continuous communication with said common pressure conduit, a bypass conduit between said pressure generator and said common pressure conduit to relieve the pressure conduit, and valve means in said bypass conduit closable to prevent bypass and thus cause the pressure generator to act directly against the common pressure conduit, said cylinders having internal peripheral grooves adjacent to said piston means for collecting liquid leaking past said piston means, and a common conduit for draining leakage liquid from said grooves.
20. A hold-down for shears and like machines, said hold-down comprising a rigid support, a plurality of hydraulic pressure actuated hold-down means supported thereby, a common pressure conduit for energizing said pressure actuated hold-down means, a continuously operating pressure generator in free continuous communication with said common pressure conduit, a relief conduit and valve means in said relief valve conduit closable to cause the pressure in said pressure conduit from said generator to act directly against said hydraulic pressure actuated hold-down means.

FREDERICK E. MUNSCHAUER.
